UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

HEEL-STIFFENER.

1,141,913.

Specification of Letters Patent.

Patented June 1, 1915.

Application filed September 3, 1913. Serial No. 787,874.

To all whom it may concern:

Be it known that I, MATTHIAS BROCK, a citizen of the United States, residing at Boston, in the county of Suffolk and State of Massachusetts, have invented certain Improvements in Heel-Stiffeners, of which the following description, in connection with the accompanying drawings, is a specification, like reference characters on the drawings 10 indicating like parts in the several figures.

This invention relates to boots and shoes, and particularly to the form or construction of one of the constituent parts of a shoe used in the manufacture thereof and known as a 15 heel stiffener or counter.

An object of the invention is to provide a heel stiffener blank which may be used as a straight stiffener in assembling the shoe or may be first molded in any suitable heel 20 shape desired, and which will be so formed as to facilitate in either case the lasting operation so that the stiffener may be properly positioned with relation to other parts of the shoe with but little effort on the part 25 of the operator and without distorting the stiffener materially from any particular shape with which it may be impressed.

In assembling upon a last the different parts of a shoe including a heel stiffener, a 30 tack is driven through the upper and stiffener into the innersole at the extreme rear end of the shoe bottom, and another tack is driven through the shoe materials into the last at the rear end face of the shoe so as 35 to fix the relation of these portions of the materials to the height of the last. Nothing, however, is done until a later stage in the manufacture of the shoe to fix the position of the stiffener wings, and it is usually found 40 after the pulling over operation that these wings have been depressed and that it is necessary to pull them up into proper relation to the last bottom preparatory to the heel seat lasting operation. One reason for 45 this condition is that the heel end face of the present day last is vertically curved and the sides of the last are shaped to cause the shoe to hug closely the ball of the heel of the wearer's foot, particularly in the case of 50 an Oxford shoe, and manipulation of the marginal edge of the upper in the assembling and pulling over operations tends to cause the upper and the stiffener to hug the rear end face of the last more especially at 55 that portion adjacent to the heel seat, as

pointed out, for example, in U. S. Patent 855,831 granted to Emery Bayard June 4, 1907. There is a tendency, therefore, for other portions of the stiffener at the rear end to stand somewhat away from the last and for the wings to be depressed from their proper position with reference to the last bottom. It is consequently necessary to pull up the stiffener wings, and this operation is especially troublesome by reason of the fact that the wings in their depressed position are located between the upper and the shoe lining which have been pulled tight in a forward direction and said wings, therefore, are difficult to reach or to grasp firmly enough to pull them up as required. The operation generally involves the use of hand pincers which it is necessary to pick up for this purpose; and aside from the time and trouble incident to this procedure it is found that in the case of a molded stiffener having a flange shaped to overlie the heel seat the use of pincers tends to bend the flange and distort the stiffener from its true shape so that the shoe materials will not fit the last as closely as desired.

An important feature of this invention resides in the provision in a heel stiffener blank of means suitably located to assist in positioning the stiffener and to facilitate the pulling up, as required, of the stiffener wings.

In the preferred embodiment of the invention the blank is formed at the wing portions with extensions suitably located to project within convenient reach of the operator when it is necessary to pull up the wings. The preferred embodiment comprises a straight blank which may be conformed as desired to the shape of the last in the assembling and lasting operations, or may be previously molded to give it the desired shape, and the wing extensions are so located that for either mode of treatment of the stiffener they will project in suitable position to provide the operator with convenient means whereby to pull up the wings without difficulty and without the liability of distorting the stiffener from its proper shape.

The invention will be understood more readily by reference to the accompanying drawings, in which—

Figure 1 is a view of a preferred form of heel stiffener blank embodying the invention, and Figs. 2 and 3 are cross sections of

the blank taken respectively on lines 2—2 and 3—3 of Fig. 1, these figures being relatively arranged upon the sheet of drawings to indicate the extent of projection of the 5 wing extensions above adjacent portions of the blank.

The blank as a whole is designated by the numeral 2, and is shown as a straight stiffener which may be used in that form in 10 the assembling of the shoe or may be molded in some suitable heel shape prior to the assembling operation. The upper portion of the blank, as viewed in Fig. 1, is that portion which will be located at or adjacent to 15 the bottom of the assembled shoe, and it will be understood that the two opposite end portions of the blank constitute the wings of the stiffener which will extend forwardly toward the shank. The upper portion 20 of the blank, as shown in Fig. 1, presents an edge of irregular contour, including a portion 4 comparatively regular in shape and of a length to extend forwardly from the rear of the heel on both sides 25 substantially to the breast line of the heel. In the blank shown the edge 4 is somewhat curved to accommodate the stiffener to a form of last in which the general contour of the rear end face of the heel in the direction of the height of the last is somewhat inclined forwardly with respect to the longitudinal axis of the last, the object being to bring all parts of the bottom portion of the 30 stiffener in such relation to the bottom of the last as to provide a flange of substantially uniform width to overlie the last bottom rearwardly from the heel breast location. For lasts of different shapes the contour of the edge portion 4 would vary correspondingly, and the present invention is 35 not limited to any particular shape of this portion of the stiffener edge.

At the ends of the edge portion 4 the stiffener edge is offset to provide extensions 45 6, these extensions in the preferred embodiment shown running from the ends of the edge 4 to the ends of the blank. These portions 6 are sufficiently extended from the main body portion of the blank to provide 50 pulling up members which will project in suitable position to be grasped readily by the operator when the stiffener wings become depressed with respect to the last bottom. It will be seen that these extensions 55 are so located that they may project farther inwardly over the insole in the assembled shoe than the main portion of the flange at the stiffener edge when this flange is shaped to lie flat upon the heel seat and 60 adjacent portions of the insole. This feature is clearly illustrated in Fig. 1 in which the dotted line shows where the stiffener will preferably be bent to form the flange. When the blank is molded before it is assembled in a shoe these extensions, if shaped 65

to lie in the same plane as the flange, will thus act as reinforcing members to assist, by contact with the insole, in preventing the stiffener wings from being depressed. In the case of such a molded stiffener, moreover, these extensions will still serve their main purpose of providing pulling up members which may be grasped if the wings are depressed so that it would otherwise be difficult to bring the stiffener to its proper 7 position.

The face of the stiffener blank in the preferred embodiment shown is skived, as usual, at its upper edge as the blank is viewed in Fig. 1, and it will be seen by referring to Figs. 2 and 3 that the skiving operation is particularly effective upon the extensions 6, reducing the thickness of these members materially in comparison with adjacent portions of the stiffener. This leaves 8 the main flange portion of the stiffener more firm and durable than it otherwise would be, and at the same time renders the extensions more flexible to the grasp of the operator, so that where pincers are used in performing the pulling up operation any bending in the case of a molded counter will take place principally at these comparatively flexible portions, and the main portion of the stiffener flange will not be injured or distorted materially from its true shape.

It will be understood that the form and likewise the length and breadth of the extensions 6 may be suitably varied as necessity or choice may dictate, and such variations are comprehended within the scope of the invention.

Having described the invention, what I claim as new and desire to secure by Letters Patent of the United States is:

1. A heel stiffener blank adapted to be assembled in a shoe as a straight stiffener or to be molded into suitable heel shape prior to assembling in a shoe and having, on the edge which is to overlie the sole in the shoe, extensions running from the shank ends backwardly a short distance to constitute pulling up members to be engaged for pulling up the stiffener ends in the lasting operation.

2. A heel stiffener blank adapted to be assembled in a shoe as a straight stiffener or to be molded into suitable heel shape prior to assembling in a shoe and having that portion which is to be located at the bottom of the shoe formed with an irregular edge comprising a portion of substantially regular contour of a length to extend around the heel from a position at or near the breast line on one side of the heel to a similar point on the other side, and extensions running from said regular portion of the edge toward the ends of the stiffener to constitute pulling up members to be engaged for pull-

ing up the stiffener ends in the lasting operation.

3. A heel stiffener blank adapted to be assembled in a shoe as a straight stiffener or to be molded into suitable heel shape prior to assembling in a shoe and having an extension from one edge constituting a pulling up member running along a portion of the stiffener that extends into the shank of the 10 shoe and adapted to project upwardly in the pulled over shoe into position to be seized by the laster for pulling up the stiffener end during the heel lasting operation.

4. A heel stiffener blank adapted to be assembled in a shoe as a straight stiffener or to be molded into suitable heel shape prior to assembling in a shoe and having that edge portion which is to be located at the bottom of the shoe of suitable contour to provide 20 for forming a relatively narrow flange to overlie the edges of the insole at the curved portion of the heel seat and a flange of greater width to extend from said narrow portion forwardly into the shank of the 25 shoe.

5. A heel stiffener blank adapted to be assembled in a shoe as a straight stiffener or to be molded into suitable heel shape prior to assembling in a shoe and having that 30 edge portion which is to be located at the

bottom of the shoe of suitable contour to provide for forming a flange of substantially uniform width overlying the edges of the heel seat, and extensions near the ends of the stiffener located to project from the 35 edge of said flange in the assembled shoe and formed to provide pulling up members whereby the wings of the stiffener may be brought to proper position in the lasting operation without distorting the shape of 40 the flange portion of the stiffener.

6. A heel stiffener blank adapted to be assembled in a shoe as a straight stiffener or to be molded into suitable heel shape prior to assembling in a shoe and having, on the 45 edge which is to overlie the insole in the shoe, extensions running from the shank ends backwardly a short distance to constitute pulling up members to be engaged for pulling up the stiffener ends in the lasting 50 operation, said extensions being skived off to render them more flexible than the adjacent portions of the stiffener.

In testimony whereof I have signed my name to this specification in the presence of 55 two subscribing witnesses.

MATTHIAS BROCK.
